MONOGRAM, ORNAMENT, AND THE LIKE

Otto F. Meissner, New York, N. Y.

Application January 18, 1937, Serial No. 121,131

4 Claims. (Cl. 40—140)

One object of this invention is the provision of a monogram, ornament, or the like, comprising two or more members or sections releasably or detachably joined together to form the complete unitary monogram or ornament which is adapted to be worn or carried in any desirable manner in the form of a brooch, pin, button, badge, or other device, and to be attached to or supported on handbags, suitcases, vanity and cigarette cases, or any other suitable article.

Another object of the invention is the provision of a monogram, ornament, or the like, with means for interlocking the various members forming the completed article, and means for preventing twisting of the various members out of the common plane of the article.

The above and other objects will become apparent in the description below, in which characters of reference refer to like-named parts in the accompanying drawing:

Referring briefly to the drawing, Figure 1 is a face view of a complete monogram.

Figure 2 is a similar view of the same monogram with the various members thereof separated from each other.

Figure 3 is a cross-sectional view taken on the line 3—3 of Figure 2.

Figure 4 is a cross-sectional view taken on the line 4—4 of Figure 1.

Figure 5 is a cross-sectional view taken on the line 5—5 of Figure 1.

Figure 6 is a face view of an ornament or insignium.

Figure 7 is a cross-sectional view taken on the line 7—7 of Figure 6.

Figure 8 is a cross-sectional view taken on the line 8—8 of Figure 7.

Figure 9 is a perspective view of one of the separate members comprising the ornament shown in Figure 6.

Figure 10 is a fragmentary perspective view of another of the members forming the same ornament.

Figure 11 is a face view of a monogram utilizing a modified construction.

Figure 12 is a similar view of the monogram shown in Figure 11, with the various members forming the same separated from each other.

Figure 13 is a cross-sectional view taken on the line 13—13 of Figure 11.

Referring in detail to the drawing, the numeral 10 indicates a relatively long main or supporting member or letter, having side arms or edges 11 and 12. The arm 11 is provided with an open slot 13 extending lengthwise in the side

edge of the arm. At spaced-apart positions, the slot 13 is filled with hollow plugs 14 having openings 15 passing axially therethrough. The plugs 14 may, however, be formed of integral extensions of the letter 10, which extensions fill the slot 13 at spaced-apart intervals. Both the plug 14 and its axial opening 13 are rectangular in cross section. The plugs 14 may be of varying lengths as desired. The letter 10 serves as the support in which the other letters 16 and 17 of the monogram are mounted. Each letter 16 and 17 has integral with one side or edge thereof, a hollow ear 18 having an axial opening 19 therein. Both the ear 18 and the opening 19 are rectangular in cross section, and the opening 19 is of the same cross-sectional dimensions as the opening 15 in the plug 14. The width and depth of the ears 18 are of approximately the same dimensions as the width and depth of the slot 13 in the arm 11. In joining the letters 16 and 17 to the letter 10, the ears 18 are inserted into the slot 13 in the spaces between the spaced-apart plugs 14. In this position, as shown in Figure 1, the openings 15 and 19 become aligned to form a single continuous opening through both the plugs 14 and the sleeves 18 extending the length of the arm 11. A pin 20 which is also rectangular in cross section, is then inserted through the top of the opening 15 in the uppermost plug 14 and passed through the said opening until it emerges at the bottom, as shown in Figure 1. The pin 20 may be provided with a head (not shown) as its upper end. In the completed monogram formed by the letters 10, 16, and 17, the latter lie in a common plane and the letters 16 and 17 which are attached to the letter 10 are prevented from swinging or turning out of that plane by the square-edged connecting members above described.

In the ornament shown in Figures 6, 7, 8, 9, and 10, one member 21 comprises the main or supporting member of the article. One side edge or arm 22 of this member is provided, integrally therewith, with a hollow extension sleeve 23 having a lengthwise-slotted opening 24 diametrically opposite the arm 22. One or more additional members 25 may be attached to the member 21, and in the illustration they consist of plates 26 whose one end 27 is rolled into a hollow ear or sleeve 28 of a diameter such that the sleeve 28 may be slidably inserted into the sleeve 23. The bounding walls 29 of the slot 24 are formed parallel with each other and with the front and back surfaces of the member 21, so that when the member 25 is thus united to the member 21, the

walls of the slot 24 will maintain the member 25 fixed in a position in the same plane as the member 21. To further lock the members 21 and 25 together, a hollow pin or tube 30 is inserted into the cylindrical opening 31 of the sleeve 28, and the ends 32 of the tube 30 are then peened over to prevent withdrawal of the tube. The members 21 and 25 may, however, be thus locked together frictionally, or a solid rivet 10 or pin (not shown) may be used instead of the tube 30 and then likewise flattened at both ends.

In the form of monogram shown in Figures 11, 12, and 13, the letters 33 and 34 are united by a modified mortise-and-tenon union. The letter 15 33 is provided on one side with extending lugs 35, and the letter 34 is provided with extending lugs 36, the latter being spaced lower than their respective counterparts on the letter 33. The lugs 35 and 36 are provided with rectangular 20 openings 37 which become aligned to form a single continuous rectangular opening when the letters are joined, as shown in Figure 11. The pin 38, also rectangular in cross section, is then inserted into the aligned openings 37 to lock the 25 two letters together in a common plane, and also to prevent turning or swinging of either of the letters out of the plane of the other, as is obvious. The pin 38 is preferably provided with a head 40. A brooch clasp 39 may be applied to the letters, 30 or to the monogram, in any desirable form or manner, as shown in Figure 13. However, any other means (not shown) of attaching the ornament or the monograms illustrated, to any article whatsoever, may be used in conjunction with the 35 invention set forth.

Obviously, modifications in form and structure may be made without departing from the spirit and scope of the invention.

I claim:

40 1. A monogram, ornament, or the like, comprising a plurality of members, means for interlocking said members, said means comprising extensions on one or more of said members, another of said members having a plurality of spaced-apart aligned slots extending lengthwise in one edge thereof, said extensions registering in said slots, and means for locking said members together.

2. A monogram, ornament, or the like comprising a plurality of relatively flat members, one of said members having a slot running lengthwise in a side edge thereof, another of said members having an ear on one end thereof, said ear registering in said slot of said first member, said side edge of said first member having an opening extending therethrough parallel with said edge, said ear having a similar opening extending therethrough, said openings being aligned when said ear registers in said slot, and a pin extending through said aligned openings to interlock said members. 5

3. A monogram, ornament, or the like, comprising a plurality of relatively flat members, one 15 of said members having an opening therein extending lengthwise through one side thereof, said member having a similarly-extending slot communicating with said opening, the others of said members having an ear on one end thereof, said 20 ears being slidably mounted in said opening and extending through said slot, the opposite walls of said slot being parallel with each other and with the surfaces of said first flat member to maintain said other members in fixed position in the same 25 plane as said first member.

4. A monogram, ornament, or the like, comprising a plurality of members, means for interlocking said members to form a unitary article of the class mentioned and for maintaining said 30 interlocked members in fixed position with respect to each other comprising ears on one or more of said members, another of said members having spaced-apart aligned slots in one edge thereof between the front and back face thereof, 35 said ears registering in said slots, and means for locking said ears in said slots comprising a pin, said ears having aligned openings passing therethrough, said other member having extensions lying between said slots said extensions having 40 similar aligned openings passing therethrough, both sets of said openings becoming aligned on insertion of said ears into said slots, said pin passing through both said sets of aligned openings, 45
